UNITED STATES PATENT OFFICE.

ALVIN D. KEENE, OF WEST MANSFIELD, OHIO, ASSIGNOR TO WESTINGHOUSE ELECTRIC & MANUFACTURING COMPANY, A CORPORATION OF PENNSYLVANIA.

FURNACE.

Application filed November 12, 1926. Serial No. 147,871.

My invention relates to furnaces and particularly to furnaces in which an automatic means is provided for discharging material therefrom.

An object of my invention is to provide an efficient automatically-operating furnace.

Another object of my invention is to provide a simple and efficient means for discharging material from a furnace.

Other objects of my invention will be obvious from the disclosure.

In practicing my invention according to the present embodiment, I provide a plurality of tiltable hearth trays that are adapted to be moved through a furnace and to be periodically and successively engaged by automatically tilting means, to discharge material from said hearth trays.

Means are provided to cause the agitation or vibration of the hearth trays at the time of discharging, thereby insuring the complete discharge of material from said trays.

It has been found that heat-treated material may stick to the hearth trays, so that not all of the material will be discharged upon tilting the trays. My invention provides means for overcoming this difficulty.

In the drawing,

Fig. 1 is a view, in vertical cross-section, of a rotary furnace embodying my invention;

Fig. 2 is a view showing a partial cross-section of a furnace in which a modification of my invention is embodied; and

Fig. 3 is a detail view showing the development of a cam surface used in the operation of my invention.

Referring to the drawing for a more complete description, a furnace 10 is provided with an outer casing 12 and an inner refractory insulating wall 14. The furnace 10 has an annular chamber 16 therein, in which are located heating elements 18, shown, by way of illustration, as being electric heating elements. These heating elements are, of course, connected to a suitable source of electrical energy (not shown). A structural steel framework 19 is provided for ensuring that the various parts of the furnace shall remain in their respective operative positions.

A plurality of hearth trays 20 are provided in the annular chamber 16 and are

so pivotally mounted on supports 22 as to be adapted to be tilted in a direction towards the outer furnace wall. The supports 22 are each, in turn, mounted on columns 24 that are secured to the rim of a wheel 26 that is mounted on the lower end of a vertical shaft 28. The columns 24 will move through an annular passageway 27 located in the bottom portion of the furnace, when the wheel 26 is rotated. The vertical shaft 28 is rotatably mounted in bearing members 29 and 30. As a further means of rotatably supporting the wheel 26, a plurality of roller members 31 are provided on which the rim of the wheel 26 rests, the rollers being located in suitable supports mounted on the bottom portion of the frame 19. A sand seal 32 may be provided to seal the passageway 27.

An annular rack 33 is secured to the wheel and is adapted to engage a gear wheel 34 that is keyed to a shaft 35. The shaft 35 is rotatably mounted in bearing members 36 and 37. Keyed to the shaft 35 is a worm wheel 39 that engages a worm screw 40. The worm screw 40 is operatively connected to a prime mover, such as an electric motor 41. It will thus be seen that, when the motor 41 is energized, the wheel 26 will be caused to turn, and the hearth trays 20 will be moved through the annular chamber 16.

A discharge conduit 44 is provided, having its outer end immersed in a quenching liquid in a tank 45. The outlet 44 is traversed by heat-treated material discharged from the hearth trays 20 when they are tilted.

Means are provided for discharging each hearth tray as it arrives opposite to the discharge outlet 44. Such means comprises a vertical shaft 46 that is reciprocated by means of a cam member 48. The cam member 48 is driven by suitable means, such as an electric motor 50, that is operatively connected to the cam member 48 by means of a worm-screw mechanism 52. The shaft 46 extends through an opening 54 in the furnace wall, the opening being large enough to permit the shaft 46 to move up and down freely therein. A roller 55 is secured to the upper end of the shaft 46 and engages a slot 56 in the drum 48, the slot extending peripherally around the surface at varying

heights so that the arm 46 will be raised and then lowered as the cam is rotated. A suitable sand seal 57 may be provided to seal the top of the opening 54. A guide member 58 may be provided at the top of the furnace structure to guide the motion of the shaft 46.

The lower end of the shaft 46 is provided with a projection 59 that has a roller 60 secured to the end thereof; for engagement with a hearth tray when the hearth tray arrives opposite to the discharge conduit 44. As is shown in the drawing, the hearth support 22 is of such dimensions as to permit the engagement of the hearth tray with the roller 60.

Means are provided for automatically so controlling the motor 50 and the motor 41 that the tilting mechanism and the conveyor mechanism will not be in operation at the same time. As one form of such means, I have shown a commutator member 61 that is keyed to the shaft 28. This commutator member has a series of metallic contact portions 62, the number being the same as the number of hearth trays, that are electrically connected to each other at their inner ends but are separated by insulation 63 at their outer ends. A brush 65 is so mounted as to be electrically connected to the contact portions 62 at all times being properly insulated from the frame. A second brush 66 is insulatedly mounted on the frame to be electrically connected to the contact members 62 successively when the shaft 28 is rotated. The brushes 65 and 66 are electrically connected to conductors 67 and 68 and in series circuit relation to the motor 50.

A contact member 70 is secured to the vertical shaft 46 but electrically insulated therefrom, and is normally in engagement with a stationary contact member 72 mounted on the furnace structure and electrically insulated therefrom. When so connected, a circuit is completed through the motor 41.

Means are provided to cause the agitation or vibration of a hearth tray 20 at the time it is being tilted. In the form of my invention shown in Fig. 1, such means comprises a narrow and substantially vertical rack 73 having a series of teeth or projections 74 thereon. At the place where the projection 58 engages the shaft 46, a suitable roller 76, that may be either cylindrical or spherical in shape, is provided and is adapted to be engaged by the teeth 74 upon movement of the shaft 46. The rack or toothed bar 73 is located against the inner wall of the furnace chamber opposite to the discharge chute.

From the foregoing description, it will be apparent that, when the motor 41 is energized, the hearth trays 20 will be caused to move through the chamber 16. When a hearth tray arrives opposite to the discharge

outlet 44, a contact 62 will engage, and will be electrically connected to, the brush 66, thereby completing the circuit through the motor 50. The motor 50, being thus energized, will cause the rotation of the cam 48 and, consequently, the upward movement of the vertical shaft 46.

Upon the upward movement of the shaft 46, the movable contact member 70 will be disengaged from the stationary contact member 72 and will thus break the circuit through the motor 41, and the movement of the hearth through the chamber 16 will, therefore, cease. Continued movement of the shaft 46 will bring the roller 60 into engagement with the free or rear end of a hearth tray 20 and cause it to rotate about its outer pivotal support.

The tilting of the hearth tray 20 will cause the discharge of material therefrom through the outlet 44. Some of the material, however, might ordinarily stick to the tray, but such material will be jarred free from the tray 20 by the bumping action produced by engagement of the roller 76 with the teeth 74, so that the material will be completely discharged from the tray.

Continued rotation of the cam 48 will restore the shaft 46, and, of course, the tray 20 to their former positions, and will bring the contact member 70 into engagement with the contact member 72, thereby completing a circuit through the motor 40, and again starting the motor 41. The rotation of the shaft 28 and the commutator member 61, because of the operation of the motor 41, will cause the disengagement of the contact member 62 from the brush 66 and thereby interrupt the circuit through the motor 50. The cycle of operation will then be repeated.

In the modification shown in Fig. 2, the conveyor mechanism and the tilting mechanism are the same as just described, with the exception that, instead of providing a toothed member 73 secured to the wall of the furnace, as in Fig. 1 teeth or projections 80 are provided on the bottom surface of the inner or free end of the tray 20. It will thus be seen that the teeth 80 will, when the tray 20 is tilted, engage a roller 82 on the extension of the vertical shaft and will cause an agitation or bumping of the tray 20, thus jarring loose any material that might otherwise stick to it. This jarring or bumping effect is somewhat similar to the bumping of a lumber wagon over a rough road.

While I have shown my hearth tray vibrator in connection with a furnace and a conveying means, of a specific type it is obvious that such vibrating means would be useful in connection with any furnace or similar device in which a movable platform is to be automatically discharged.

While I have shown and described, for

purposes of illustration, a particular form of my invention, it may, of course, be embodied in other forms without departing from the spirit and scope thereof, as set forth in the appended claims.

5 I claim as my invention:

1. In a furnace, the combination with a movable hearth, of means for jarring said hearth.

10 2. In a furnace, in combination, a movable hearth, means for causing said hearth to travel through the furnace, means for moving said hearth to cause the discharge of material therefrom, and means associated with said discharge means to cause the hearth to vibrate at the time of discharge.

15 3. In a furnace, a tiltable hearth, means for tilting said hearth, and bumping means associated with said tilting means for agitating said hearth.

20 4. In a furnace having a conveyor therein, a plurality of tiltable hearths mounted on said conveyor, means for periodically and successively tilting said hearths, and means associated with said tilting means for agitating said hearth.

25 5. In a heat-treating furnace, in combination, a movable hearth, means for moving said hearth for discharging heat-treated material therefrom, and a series of projections adapted to engage said hearth-moving means for causing the vibration of said hearth when material is discharged.

30 6. In a heat-treating furnace, in combination, a tiltable hearth, reciprocating means for tilting said hearth to cause the discharge of material therefrom, and stationary teeth for engaging said reciprocating means to

cause an agitation of the hearth when it is being tilted.

40 7. In a heat-treating furnace, in combination, a conveyor, a plurality of tiltable hearth trays on said conveyor, a reciprocatory shaft having means for periodically and successively engaging said hearth trays to tilt the same, a substantially vertical member having projections thereon, and a roller member on said shaft adapted to engage said projections upon movement of said shaft, whereby the hearth trays are agitated when tilted.

45 8. In a furnace, the combination with a pivotally mounted hearth, and means for tilting said hearth, of means for causing jarring of the hearth during the tilting action.

50 9. In a furnace, the combination with a pivotally mounted hearth, normally located in a substantially horizontal position, a vertically movable lever having a roller thereon for tilting said hearth, and means operatively engaged by the roller during the tilting operation for effecting jarring of the hearth.

55 10. In a furnace, the combination with a plurality of pivotally mounted hearth trays, and motor-actuated means for moving said hearth trays through the furnace chamber, of a motor-actuated lever member for successively tilting said trays and means operatively engaged by the lever member during the tilting operation for effecting jarring of said tray.

60 In testimony whereof I have hereunto subscribed my name this 4th day of November, 1926.

ALVIN D. KEENE.
